The ornamental design for a ceiling fan heater, as shown and described.

DESCRIPTION

FIG. 1 is a side elevational view of a ceiling fan heater showing my design, the other sides being identical to that shown;

FIG. 2 is an enlarged top plan view taken along line 2—2 and looking in the direction of the arrows of the ceiling fan heater of FIG. 1;

FIG. 3 is an enlarged bottom plan view of the ceiling fan heater of FIG. 1.

The broken line showing of a ceiling fan in FIG. 1 is for illustrative purposes only and forms no part of the claimed design.
